UNITED STATES PATENT OFFICE.

STEPHEN SZARKA, OF BRANTFORD, ONTARIO, CANADA.

SHOE CLEANING AND POLISHING DEVICE.

1,119,201.

Specification of Letters Patent.

Patented Dec. 1, 1914.

Application filed March 9, 1914. Serial No. 823,487.

To all whom it may concern:

Be it known that I, STEPHEN SZARKA, a subject of the King of Hungary, residing at Brantford, in the Province of Ontario and Dominion of Canada, have invented 5 certain new and useful Improvements in Shoe Cleaning and Polishing Devices, of which the following is a specification.

This invention relates to new and useful 10 improvements in shoe cleaning and polishing devices.

The primary object of the present invention is to provide a machine readily operable by the user thereof or by a servant if 15 desired to clean and polish the shoes of the wearer with extreme rapidity and in a high degree of efficiency.

A further object is to provide a cabinet machine adapted to have the foot of the 20 customer readily positioned therein for contacting manually operable brushing and cleaning devices of different degrees of coarseness under the actuation of the customer or a servant.

25 A further object is to provide a portable cabinet having a dirt receptacle for receiving the accumulations from a plurality of graded shoe cleaning brushes journaled therein and manually operable through a rack and pinions which are actuated by the customer or a servant through a reciprocating hand lever.

With these general objects in view and others that will appear as the nature of the 35 invention is better understood, the same consists in the novel combination and arrangement of parts hereinafter fully described, illustrated in the accompanying drawings and pointed out in the appended 40 claims.

In the drawings forming a part of this application and in which like reference numerals designate corresponding parts throughout the several views:—Figure 1 is 45 a plan view of the device. Fig. 2 is a side elevation thereof partly in vertical section through the gear case upon line 2—2 of Fig. 1, and Fig. 3 is a vertical sectional view upon line 3—3 of Fig. 1.

50 Referring more in detail to the drawings, the numeral 10 designates a cabinet which is substantially rectangular in cross section and provided with a sliding drawer 11 in the bottom thereof and adapted to receive the dirt from the shoes which are cleaned and polished in the cabinet by means

of the brushes 12. The said brushes are graded in degrees of coarseness, the lower brush being the coarser while the top brush is finer or softer and especially adapted as a 60 finishing or polishing medium. The axles 13 of said brushes are trunnioned through the opposite sides 14 of the cabinet and at one side thereof are extended and have meshing gears 15 rigidly secured theron. 65 The said gears decrease in size from the top to the bottom gear while the latter is in mesh with the teeth of a longitudinally slideable rack 16 which is mounted upon a headed pin 17 extending through a longitudinal 70 slot 18 of said rack. A hand operating lever 19 is pivoted as at 20 to one of the cabinet sides 14 and has its lower end pivoted by the bolt or pin 21 with an end of the rack 16. The lever 19 is resiliently secured to 75 the adjacent side of the cabinet by means of a coil spring 22.

The rear side of the cabinet is closed by the wall 23 while the forward inclined side is open substantially the entire length and 80 provided with inwardly slanting cross strips 24 positioned adjacent each of the brushes and adapted for serviceably positioning the shoe of a customer in operative contact with the desired one of the brushes, 85 a portion of such a shoe being shown at 25 in dotted lines in Fig. 3.

A gear casing 30 is secured to the side of the cabinet and incloses the pinions 15 while 90 said casing is broken away at the bottom thereof as shown in Fig. 1 to allow the lower pinion to extend exteriorly of the casing to mesh with the teeth of the rack 16. It will be seen that the inclined upper face of the sides 32 of the drawer 11 abuts the under 95 surface of the lower shoe rest 24 when the drawer is completely closed and thus prevents any escape of the contents of the drawer. It will also be seen that the spring 22 is adapted to normally position the operating lever 19 vertically or if desired may normally position the same to the best advantage for grasping by the patrons or proprietor of the cabinet when employed in the business of shoe cleaning and polishing. 100

The complete operation of the device will now be apparent, the shoe being positioned upon the lower strip 24, the customer or another party if desired reciprocates the operating lever 19 thus imparting a longitudinal sliding movement to the rack 16 and whereby all of the gears 15 and their axles 110

13 as well as the brushes 12 are revolved in alternating directions and the lower or coarser brush having operated upon the shoe, the latter is placed successively in contact with the two upper brushes and thoroughly cleaned and polished while all dirt or foreign matter is precipitated into the base drawer 11 and easily removable therefrom while the dust incident to the operation is prevented from escaping by means of the inclosing cabinet.

While the forms of the invention herein shown and described are what are believed to be preferable embodiments thereof, it is nevertheless to be understood that minor changes may be made in the form, proportion and details of construction without departing from the spirit and scope of the invention as set forth in the appended claims.

29 What is claimed as new is:—

1. A device of the class described comprising an inclosing cabinet having an inclined open front, a dirt receiving drawer removably positioned in the base of the cabinet, a plurality of brushes of different degrees of coarseness journaled in the opposite sides of said cabinet, foot rest

strips secured at the front of said cabinet adjacent each brush and extending obliquely inward, pinions upon adjacent ends 30 of the brush axles meshing with each other, a toothed rack slidably mounted and normally meshing with the lower one of said pinions, a hand lever operatively linked to said rack, a spring between said lever and cabinet at 35 attached to the lever below its fulcrum point to retain the lever when at rest in position in front of the rear edge of the back of the cabinet.

2. The combination with a cabinet having 40 an open inclined front portion, oblique foot-rest strips arranged at the front of the cabinet and secured to the side walls of the latter, rotary brushes within the cabinet adjacent to said foot-rests, and a drawer below said brushes having an inclined upper edge to engage the lower one of said rests.

In testimony whereof I affix my signature in presence of two witnesses.

STEPHEN SZARKA.
